UNITED STATES PATENT OFFICE

160,476

NAME PLATE

Dudley P. Combs, Newton, Iowa, assignor to The Maytag Company, Newton, Iowa, a corporation of Delaware

Application December 14, 1948, Serial No. 150,156

Term of patent 14 years

(Cl. D1—7)

To all whom it may concern:

Be it known that I, Dudley P. Combs, a citizen of the United States, residing at Newton, in the county of Jasper and State of Iowa, have invented a new, original, and ornamental Design for a Name Plate, of which the following is a specification, reference being had to the accompanying drawing, forming a part thereof.

In the drawing:

I claim:

The ornamental design for a name plate, substantially as shown.

DUDLEY P. COMBS.
